UNITED STATES PATENT OFFICE.

JOHN ERDELYI AND LEO DAVIS, OF NEW YORK, N. Y.

SELF-PROPELLED SLED.

SPECIFICATION forming part of Letters Patent No. 766,173, dated August 2, 1904.

Application filed April 26, 1904. Serial No. 204,939. (No model.)

To all whom it may concern:

Be it known that we, JOHN ERDELYI and LEO DAVIS, both residents of Brooklyn, Kings county, in the State of New York, have invented certain new and useful Improvements in Self-Propelled Sleds, of which the following is a specification.

Our invention relates to that class of sleds which are adapted to be manually propelled by means of actuating-levers and propelling- rods; and the present invention has for its object to provide a simplified and inexpensive sled of this character wherein the stroke of the propelling-rods may be readily regulated and wherein also the jarring and undue bouncing effects heretofore encountered in such sleds by the action of the propelling-rods striking against the ground will be practically eliminated or reduced to a minimum.

To these and other ends, which will herein-after appear, our invention consists in the novel features of improvement and combination and arrangement of parts hereinafter set forth and finally summarized in the appended claims.

Reference is to be had to the accompanying drawings, forming part hereof, wherein—

Figure 1 is a perspective view of a sled embodying our invention, and Fig. 2 is an enlarged vertical central section of the cushioning means detached from the sled.

Referring to the accompanying drawings, in which like numerals of reference indicate corresponding parts, 1 indicates the top or seat of an ordinary sled. 2 are the vertical posts supporting the same; 2^a 2^b, the runners, and 2^c indicates the cross-bar or foot-rest connecting the runners at the front, the same being preferably disposed on a plane slightly below the seat 1.

13 indicates an actuating hand-lever, pivoted at 15 to a bracket or support 14 upon the front post 2.

6 indicates what we term the "propelling" or "pusher" rod or staff, the extreme forward end thereof being threaded and bent inwardly at a right angle, so as to provide a pivot-pin adapted to enter one of the series of openings 12 in the actuating-lever, the same

being retained in position by a nut 10, as shown.

3 indicates a bracket attached to the rear post 2 and provided with a slot 4, vertically disposed, in which loosely slides a stud or pin 5, suitably confined in said slot and which is provided with a head having an angularly-disposed opening and with an angularly-disposed hollow extension or sleeve 5^a, registering with the opening in the head, through which the propelling-rod 6 passes and is guided in its actuating movements.

8 indicates a spiral coiled spring wound upon the propelling-rod 6, and 9 indicates a lug or abutment against which the said spring exerts its forward pressure, so as to normally maintain the actuating-lever 13 in the position shown in the drawings and assist in bringing the same forward to this position after each backward movement thereof.

5^b indicates a flange or abutment upon the sleeve 5^a, against or to which the other end of the spring 8 impinges or is secured; but the sleeve 5^a may be dispensed with and the spring 8 secured directly to the head of the sliding stud 5 in suitable manner.

To prevent undue jarring or vertical lifting or bouncing of the sled caused by the rapid striking of the end of the propelling-rod against the ground during the propelling operation, we provide what may be termed a "cushioning" device, consisting of a spiral spring 5^c, vertically disposed, the upper end of which is preferably secured to the vertically-movable stud 5, the lower end of said spring being secured to a short extension or ledge 3^a of the bracket 3. The rear end of the propelling-rod 6 is preferably provided with a slight downwardly-bent point 7 to readily penetrate the snow or ice in the propelling movements of the rods 6.

The sled is provided with the described devices in duplicate, one on each side, as shown, and in operation the person seated upon the sled places his feet against the foot-rest or rod 2^c and manipulates the pivoted levers 13 back and forth, thereby actuating the connected propelling-rods 6 in obvious manner, which by their resistance to the ground tend

to push the sled forward. The propelling-
5 rods being yieldingly held by their connection
with spring 5^c and movable sliding stud 5, a
cushioning effect is produced, whereby the
tendency to jarring or lifting of the sled by
the rapid actuation of the propelling-
practically eliminated or reduced to a mini-
mum.

By means of the graduated series of open-
10 ings 12 in the actuating-levers 13 we have pro-
vided a simple and efficient means for regulat-
ing the stroke of the propelling-
rods, it being
merely necessary in order to obtain a shorter
15 or longer stroke to connect the forward ends
of the propelling-
rods to the desired opening
in the lever 13 in obvious manner.

It will be noted that the parts constituting
our improved propelling and cushioning
means may readily be attached to sleds of ordi-
20 nary construction without reconstruction
of such sleds.

It will also be understood that some of the
minor details of construction hereinbefore
described may be varied without departing
25 from the spirit of our invention.

What we claim, and desire to secure by Let-
ters Patent, is—

1. The combination with a sled, of propel-

ling-
30 rods, pivoted actuating-levers therefor,
springs for normally maintaining the propel-
ling-
rods out of contact with the ground, and
vertically-movable studs connected to the pro-
pelling-
rods, substantially as and for the pur-
pose described.

2. The combination with a sled, of suitably-
35 mounted propelling-
rods and actuating-
levers therefor, a slotted bracket at the rear of the
sled, a spring-
pressed stud or pin slidably
confined in said slot, and having an apertured
head through which the propelling-
rod passes. 40

3. The combination with a sled, of a pivoted
actuating-lever, a propelling-
rod detachably
connected therewith, a bracket secured to the
sled, provided with a vertically-disposed slot,
45 a stud confined in and slideable along said slot,
the stud having a transverse opening in its
head in which the propelling-
rod is guided,
and a spring connected with said stud, all ar-
ranged substantially as and for the purpose
herein shown and described. 40
